UNITED STATES PATENT OFFICE.

LOLLEY THOMAS PATE, JR., OF NORPHLET, ARKANSAS.

HAY-PRESS.

1,106,580.

Specification of Letters Patent. Patented Aug. 11, 1914.

Application filed December 14, 1912. Serial No. 736,791.

To all whom it may concern:

Be it known that I, LOLLEY THOMAS PATE, Jr., a citizen of the United States, residing at Norphlet, in the county of Union and State of Arkansas, have invented certain new and useful Improvements in Hay-Presses, of which the following is a specification, reference being had therein to the accompanying drawing.

This invention relates to hay presses, and has for its object the production of an efficient press whereby the plunger rod may be readily released so as to allow the same to automatically return to its normal position.

Another object of this invention is the production of an efficient press whereby the hay may be easily pressed in the press box and removed therefrom after the hay has once become pressed.

With these and other objects in view, this invention consists of certain novel constructions, combinations and arrangements of parts, as will be hereinafter fully described and claimed.

In the drawings:—Figure 1 is a top plan view of the press. Fig. 2 is a side elevation thereof. Fig. 3 is a central horizontal section similar to Fig. 5 showing the plunger in a partially compressed position. Fig. 4 is a section taken on line 4—4 of Fig. 3. Fig. 5 is a section taken on line 5—5 of Fig. 2.

By referring to the accompanying drawings, it will be seen that the press comprises a pair of parallel supporting members 1, upon which members is supported the press box 2. The press box comprises a pair of transversely extending members 3, which members support the upper transversely extending members 4. Vertically extending press members 5 are formed upon the box, and the upper transversely extending members 4 and the transversely extending members 3 are connected by the vertically extending rod 6, which rods have nuts 7 threaded upon their upper ends for clamping the transversely extending members 3 and 4 upon the vertical press members 5. Metallic tie members 8 pass over the upper ends of the transversely extending members 4 upon each side of the press, as illustrated in Fig. 2, and have their intermediate portions downwardly inclined and secured to the parallel base members 1 by means of

bolts 9. The metallic tie members 8 pass upwardly from the forward ends of their intermediate portions so as to overhang the top of the drum supporting casing 10, and these tie members are secured to each side of the drum supporting casing by means of bolts 11.

The drum supporting casing comprises a pair of end walls 12, through which end walls 12 passes the plunger 13. A top member 14 is supported by the end walls 12, and the bottom of the drum supporting casing constitutes a platform 15. A roller 16 is interposed between the top 14 and the platform 15, and has its reduced ends 17 positioned within the metallic lined apertures 18 in said top and platform. The metallic lined apertures 18 form efficient bearings for the roller 16. The roller 16 engages the outer face of the plunger 13 so as to hold the plunger 13 in engagement with the gear wheel 19. A rotating drum or shaft 20 is journaled in the top 14 and platform 15, the lower reduced end 21 of the shaft 20 fitting in the metallic lined apertures 22 of the platform 15. A lever 23 straddles the reduced end 21 of the shaft 20, as illustrated in Fig. 9, and engages the shoulder 24 formed upon the lower end of the shaft 20 for facilitating the raising of the shaft for disengaging the gear wheel 19, which gear wheel 19 is keyed to the shaft 20, as illustrated in Fig. 4. The upper end of the shaft 20 is squared as indicated at 24, and to this shaft is connected the winding beam 25. Of course, it should be understood that any other desired driving means may be secured to the upper end 24 of the shaft 20, as for instance, a pulley, but in the presence instance a beam has been illustrated for facilitating the compressing of the plunger by attaching draft animals to said beam.

A lever 23 is pivotally secured to the platform 15 by means of a bolt 26 which loosely secures the lever 23 to the platform 15 by passing through the elongated slot 27 formed in the lever 23. The outer end or handle 28 of the lever 23 is off-set as illustrated in Fig. 3 for extending parallel with the outer edge of one of the base beams 1. The bolt 26 so secures the lever 23 to the platform 15 as to allow the lever to have a free vertical swing for disengaging the gear wheel 19 from the ratchet teeth 29 of the plunger 13.

The press box 2 is provided with a plural-

ity of spaced parallel members 30 upon each side, and a plunger head 31 is carried by the plunger rod 13 and is provided upon its inner surface with a pair of grooves 32 the 5 ends of which register with the spaces between the members 30, for facilitating the passage of binding wire around the hay or other material to be pressed within the press box. The outer end of the press box 2 is 10 closed by means of a door 33, which door is hinged to the casing by means of the hinges 34. A lever 35 is pivotally secured to the door at 33, and this lever engages the oppositely extending hooks 37 formed upon the 15 press box 2, thereby firmly holding the door in a closed position. A hopper 38 is formed above the entrance opening 39 of the press box 2 for facilitating the entrance of hay or other material to be pressed within the press 20 box.

A coil spring 40 is connected to one of the horizontally extending base members 1 by means of an eye 41, and the opposite end of the coil spring is connected to the under 25 face of the plunger 13 by means of an eye 42. The plunger 13 is also provided upon the top with projecting lugs 43, which projecting lugs engages the rear face of the plunger head 31 for bracing the same. A 30 cleat 44 is formed upon one side of the plunger 13 and may be engaged by means of the locking member 45, which locking member or lever 45 is pivotally secured to one of the transversely extending base members 3 of 35 the press box, as indicated at 46. This member 45 may be swung so as to engage the rear end of the cleat 44 and thereby hold the plunger in said press box and relieve the strain from off the draft animals or winding 40 mechanism which coöperates with the drum or shaft 20. A stop lug or abutment 47 is formed upon the upper face of the plunger 13 and engages one of the side walls 12 of the drum supporting box so as to limit the 45 returning movement of the plunger after the plunger 13 has been released from the winding mechanism.

A draft member 48 is connected to the front of the press and is provided with an 50 eye 49 for facilitating the attaching of the

draft animals to the press for conveying the press from place to place.

From the foregoing description, it will be seen that the plunger 13 may be projected into the press box, and when so desired the 55 plunger may be locked in the press box by the lever 45 engaging the cleat 44. When it is desired to release the plunger 13 from the press box, the lever 45 may be released from the cleat 44 and the plunger 13 will return to its normal position by means of the spring 40 pulling rearwardly upon the plunger 13 as soon as the gear wheel 19 has been released from the ratchet teeth 29 formed upon the rack bar or plunger 13, or, in other 60 words, drawn to the position shown in dotted lines in Fig. 4.

From the foregoing description, it will be seen that a very efficient press has been produced whereby the plunger will automatically return to its normal position as soon as the driving mechanism has been released therefrom.

What is claimed, is:—

In a device of the class described the combination with a press box, a frame, a plunger rod working in said press box and supported upon said frame, a roller, an operating lever, a gear carried by said operating lever, said plunger rod provided with 75 teeth upon one side thereof for facilitating the moving of said plunger longitudinally within said press box as said lever is swung, said roller firmly holding said plunger rod in engagement with said gear wheel, tension 80 means engaging said plunger rod and said frame for normally drawing said plunger to a retracted position, said plunger provided with a notch upon one side thereof, and a pivoted lever carried by said frame and 85 adapted to be swung in engagement with said notch for locking said plunger in a compressed position.

In testimony whereof I hereunto affix my signature in presence of two witnesses.

LOLLEY THOMAS PATE, JR.
